UNITED STATES PATENT OFFICE.

SAMUEL MOORHOUSE, OF LEEDS, ENGLAND.

SPINNING, DOUBLING, TWISTING, AND LIKE MACHINE.

Application filed April 26, 1921. Serial No. 464,501.

To all whom it may concern:

Be it known that I, SAMUEL MOORHOUSE, a subject of the King of Great Britain, and resident of Wellington Foundry, Leeds, in the county of York, England, have invented a certain new and useful Improvement in Spinning, Doubling, Twisting, and like Machines Used in the Production of Yarns or Threads of Fibrous Substances, of which the following description, having reference to the accompanying sheets of drawings, is a specification.

It relates to spinning, doubling, twisting and like machines used in the production of yarns or threads of fibrous substances, and to that class wherein the yarns are wound either upon the bare spindle or upon tubes or bobbins carried by said spindle to form a cop or spool, and wherein the formation of the nose of the cop is produced by the winding of the threads within an inverted conical cup, and my present invention consists in an improved construction and arrangement of the conical cup, the spindle which is to rotate loosely within same, and means for supporting said spindle together with means for transmitting motion to the cup as well as to the thread guide. My said invention further consists in the application of means whereby said thread guiding actions and the retarding or dragging of the spindle may be efficiently carried out.

In the accompanying sheets of drawings which are illustrative of my invention.

Fig. 1 is front elevation of sufficient of a spinning or like machine to show the application thereto of my improved parts.

Fig. 2 is a sectional end elevation of the parts shown by Fig. 1 as seen in the direction looking from right to left of said figure.

Fig. 3 is a similar view to Fig. 2 and illustrates my several devices as seen looking from left to right of said Fig. 1.

Fig. 4 is a sectional elevation drawn to an enlarged scale showing the construction and arrangement of my improved inverted cup device and parts in connection therewith.

Fig. 5 is a sectional elevation showing the inverted cup and thread guide in detail drawn to an enlarged scale in order to illustrate the bearings and supports for said parts.

Fig. 6 is a plan of certain of the parts shown by Fig. 5.

Fig. 7 is a sectional elevation drawn to an enlarged scale of a part where the drag is put upon the spindle as is hereinafter explained.

Figs. 8 and 9 are sectional elevation and plan of an alternative method of counterbalancing the spindle and its supports.

A indicates the end frames of the machine and B B¹ the longitudinal binding rails of said machine.

In carrying my invention into effect the conical cups 2 are mounted to rotate freely by taking over fixed supporting sleeves 3 which are fixed in the binding rail B by nuts α at one end and shoulders 3^a resting upon the upper surface of said rail B so that when each of said sleeves 3 is bound by its nut α and by a projecting pin 3^b taking into the rail B it is firmly and securely held in position.

The cup 2 has within its base piece 2^a antifriction bearings w so mounted that said antifriction bearings w may be supported laterally by the sleeve 3 within, while said base piece 2^a has also screwed into it the upper end of a sleeve 4 which extends vertically over the sleeve 3 in order that said sleeve 4 may have fixed upon it at its lower end a driving pulley or wharle 5.

Within a cavity formed in extension of the pulley 5 I mount antifriction bearings 2^b which are supported laterally and vertically by the sleeve 3 and its shoulder or collar 3^a as shown by Fig. 5.

Extending from the cups 2 are the vertical arms or projections 6 which reach upwardly so that they may have fixed upon their upper extremities discs 7, each of which discs may be in the form of a cross arm to suit the two vertical projections 6 as will be understood, but I preferably make use of the disc formation as same may be more readily balanced.

Mounted within the central opening in each disc 7 is the antifriction bearing 7^a which is mounted to rotate upon a stud 7^b fixed in the bracket 8. The stud 7^b has an opening or guide-eye *c* made through it so that the threads *d* as they are spun pass through this guide-eye *c* in order that they may be wound around one or the other of the legs 6 and pass forward through a guide-eye 10 2^f mounted upon the flange of the cups 2. The guide eye 2^f is preferably of hardened metal or it may be of porcelain or like material which will resist wear and which will permit said guide eye to be replaced when worn. Covering the disc 7 at the upper end of the projections 6 is a shield 8^a which prevents the gathering of loose fibres and otherwise protects the bearing within the disc 7.

By making use of the bearings for the 20 cups 2 and their driving pulleys as hereinbefore described, said parts are supported laterally at both of their extremities, as well as in a somewhat central part hence same are held against vibration.

25 Each of the cups 2 and the parts in connection therewith is arranged to have encircling the sleeve 4 upon which it is mounted an annular part 9 which is supported by antifriction bearings 10 carried by the lifter 30 plates 11 which are mounted upon the sliding brackets 12. Said annular parts 9 have each extending from their upper surfaces two projections 9^a and 9^b which take into or through grooves formed in the edge of the 35 base part 2^a of the cup 2.

At the upper end of the projection 9^b is mounted a thread guide 9^c so that the thread *d* passing through the guide-eye *c* in the stud 7^b after being wound around one or the 40 other of the arms or projections 6 will pass through the guide-eye 2^f and through the thread guide 9^c in order that by extending from said thread guide 9^c through the slot 2^g made in the cup 2, the winding operations 45 may be carried out as is hereinafter described.

Taking loosely within each of the cups 2 and the sleeves 3 is a spindle 13 which reaches from within the cups 2 down to the 50 foot steps 14 carried by the sliding brackets 14^a beneath. These spindles 13 have their lower ends of conical formation to enable them to rotate freely upon their said foot-steps 14, and they are held in position by covers *d* taking over a shoulder *f* at the lower end of said spindle 13, hence although the spindle 13 may freely rotate upon its 55 foot step 14 it is yet rendered undetachable on account of said cover *d* engaging with the shoulder or collar *f*.

The sliding bracket 14^a which supports the foot step 14 is arranged to slide upon bearings 15 which are secured to the binding rail B and these brackets 14^a together with the parts which they support are counter-

balanced by a weight 16 being suspended by cords 16^a taking over guiding pulleys *g* and *h* and being fixed to said brackets 14^a.

Instead of the brackets 14^a and parts carried by same, being counterbalanced by the 70 weighted cords 16^a I may have racks 14^b secured to them and arranged to slide upon the bearings 15 so that pinions 14^c may mesh therewith while running loosely upon their supporting shaft 14^d (see Figs. 8 and 9). 75 Engaging with these pinions 14^c are racks 14^f which are formed upon the counterbalancing weights 14^g. These weights 14^g are formed to slide vertically as they are guided by the bearings 15 and the shaft 14^d. Detachable weights *x*¹ are arranged to take over projections *x* so as to adjust the weights 14^g to the work required of them.

The sliding brackets 14^a have extending from them projections 14^h which the attendant may use as pedals or otherwise to operate said sliding brackets 14^a to cause them to descend in order to withdraw the spindles 13 from within the cups 2 and the cups 18 that have been wound upon them 90 thus facilitating the process of doffing.

In order to apply drag to, or to retard the rotary movements of the spindles 13 during the process of spinning, grooves or keyways 13^a are formed therein so that a pin 19 extending within a bush 20 may slide within said groove 13^a while the spindle 13 slides freely through same vertically in the manner and under the conditions hereinafter described. This bush 20 has a flange 20^a 100 which takes into a recess in a drag pulley 21 so that said drag pulley is firmly fixed upon the sleeve or extension of the bush 20 and is made to fit snugly so as to be at all times guided in its rotary motions by its laterally supporting bearings 22 which are fixed within the drag rail 23.

By the bush 20 fitting snugly in the bearing 22 as described and by said bush 20 being entirely clear of the spindle 13 although rotary motion is transmitted to the drag pulley 21 by the rotary motions of the spindles 13 yet the pressure of the drag cord 24 (which acts in well known manner under the actions of the weight 25) is entirely withstood by the bush 20 acting against its bearing 22 thus leaving the spindle 3 entirely free from any lateral pressure thereon, although the dragging or retarding of its rotary motions is efficiently effected by said drag pulley 21.

As is hereinbefore explained the sliding brackets 12 upon which the lifter plates 11 are mounted are arranged to be guided by their bearings or supports 26 secured to the cross rail B so that their rack surfaces may be operated by their toothed quadrants 27 fixed upon a shaft 28 which extends lengthwise the machine. This shaft 28 derives its oscillatory movement (which enables it to 120

cause the lifter plates 11 to rise and fall through the medium of a box cam 29 mounted in well known position and operated through well known trains of gearing used 5 in other machines for similar purposes.

As this cam 29 rotates it causes a lever 30 to oscillate upon its stud 30^a by means of an antifriction pulley 30^b taking within the groove in said box cam 29. The horizontal 10 arm of the lever 30 has an adjustable connecting rod 31 pivoted upon it and the lower end of this connecting rod 31 is connected to a lever arm 32 fixed upon the cross shaft 28 so that the oscillatory movements 15 of the lever 30 are transmitted to the lifter plates 11.

Since it is desirable that all back lash should be taken out of the parts which operate the lifter plates 11 throughout all the 20 rising and falling movements of same in order that the thread guides 9^c may be more evenly operated, I make use of retracting springs 33 which have flexible connections taking over quadrants 34 so that the actions 25 of the cam 29 have at all times the retracting forces of these springs 33 to overcome, hence the anti-friction pulleys 30^b are throughout all the movements of the cam 29 kept in proper engagement with the cam 30 surface.

The actions of the several parts are as follows:—

On the threads *d* passing between their well known drawing, receiving and delivery 35 rollers each one of them is conducted through its guide-eye *e*, is then wound around one or other of the projections 6 and conducted through the guide-eye 2*f* so as to pass through the thread guide 9^c and 40 through the slot 2^g to be wound upon the spindle 13.

At this time the spindles 13 are in their lowest positions with their upper ends within or nearly within the cups 2.

On the machine being started into operation the driving and guiding cylinders 35 and 36 transmit (by the driving bands 37) rotary motion to the driving pulleys 5 by which means the cups 2, as they begin to 50 rotate, wind the threads *d* upon the spindles 13 or upon tubes or spools mounted thereon.

After the winding operations commence the thread guides 9^c are caused to rise and fall by the lifter mechanism in order to 55 guide the threads *d* to be wound in a spiral manner upon the spindle 13 within the cup 2.

As the number of coils increase so that they begin to press upon the inner walls of the cups 2, they are forced in an upward direction and when thus moving they carry 60 with them the spindles 13. These latter are brought to have the succeeding coils of threads wound upon them until the cups are formed of the desired length.

The doffing of the cups is effected as here-

inbefore described and the re-starting of the machine into operation is carried out in well known manner.

Such being the nature and object of my said invention, what I claim is:—

1. In a machine of the character described, the combination of a vertically positioned spindle, means for reciprocating said spindle, a substantially conical shaped cup surrounding the spindle with the smaller end directed 70 downward, said cup being supported in an upright position at both its upper and lower ends, and means for rotating the cup.

2. In a machine of the character described, the combination of a vertically positioned 80 spindle, means for reciprocating said spindle, a substantially conical shaped cup surrounding the spindle with the smaller end directed downward, said cup being supported by vertically stationary, antifriction bearings at 85 both its upper and lower ends, and means for rotating the cup.

3. In a machine of the character described, the combination of a main frame, a substantially conical shaped cup supported in a vertical position on the frame with its smaller 90 end directed downward, means for rotating said cup, a spindle extending axially into said cup through its lower end, and means for reciprocating the spindle relative to the 95 cup.

4. In a machine of the character described, the combination of a main frame, a substantially conical shaped cup supported in a vertical position on the frame with its smaller 100 end directed downward, means for rotating said cup, a spindle extending axially into said cup through its lower end, lateral bearings for the upper and lower ends of the cup, thread guiding devices for conducting 105 thread from the exterior of the cup to the spindle therein, including an axially positioned eye within the upper bearing for the cup, and means for moving the spindle vertically within the cup.

5. In a machine of the character described, the combination of a main frame, a substantially conical shaped cup supported at its upper and lower ends in the frame, with its smaller end directed downward and having 115 a thread receiving slot in its side wall and opening through its upper edge, a spindle extending axially into the cup, means for guiding thread through said slot in the cup onto the spindle therein including a reciprocating member extending parallel to the spindle outside of the cup, means for rotating the cup in its bearings on the frame, and means for moving the spindle vertically within the cup.

6. In a machine of the character described, the combination of a supporting frame, a substantially conical shaped cup, having its smaller end directed downward, mounted in 120 bearings in the frame above and below its 125

top and bottom, said cup having a thread receiving slot in its side wall and opening through its upper edge, a reciprocable spindle extending axially into the cup through its lower edge, means for guiding thread through said slot in the cup to the spindle therein, means for rotating the cup, and means for counterbalancing the spindle and normally holding it stationary and permitting vertical movement thereof relative to the cup as thread is wound thereon.

7. In a machine of the character described, the combination of a frame including a horizontal supporting rail, a substantially conical shaped cup having its smaller end directed downward, a bearing on said rail, supporting the lower end of the cup, arms extending upward from the cup, a disc connecting the upper ends of said arms, a bearing on the frame for said disc, means for rotating the cup, a spindle extending axially

into the cup through its lower end, means for guiding thread into the cup and to the spindle therein, and means for moving the spindle vertically relative to the cup.

8. In a machine of the character described, the combination of a supporting frame including a horizontal rail, a substantially conical shaped cup, having its smaller end directed downward, supported at its lower end in a bearing on the rail, a second bearing for the upper end of the cup arranged above the rail, a spindle extending axially into the cup through the lower end thereof, means for guiding thread into the cup and onto the spindle therein including a reciprocating guide carried by a sleeve surrounding the spindle below the cup, means for rotating the cup, and means for moving the spindle vertically relative to the cup.

S. MOORHOUSE.
